Application February 2, 1954, Serial No. 28,782

Term of patent 7 years

(Cl. D54—12)

Fig. 1 is a front elevational view of a spoon, showing my new design;

Fig. 2 is a rear elevational view thereof;

Fig. 3 is a fragmentary sectional view taken on the line 3—3 of Fig. 1;

Fig. 4 is a cross-sectional view taken on the line 4—4 of Fig. 1.

Fig. 5 is a side elevational view thereof in a 90° relationship to Fig. 1.

The dominant feature of the design resides in the portions shown in full lines.

I claim:

The ornamental design for a spoon or similar article, substantially as shown and described.
